TIME ANNOUNCING DEVICE

Michael J. Sullivan, Chicago, Ill.

Application January 21, 1932, Serial No. 587,875

6 Claims. (Cl. 274—9)

This invention relates to an announcing machine which is adapted to be connected in a manner described to a standard clock and to cooperate with and be controlled by said clock 5 to intermittently announce the time at regular intervals. The announcing machine employs novel means for intermittently moving a sound reproducing element in and out of engagement with a disc or the like on which the announcements 10 have previously been recorded in a manner similar to that used in the manufacture of phonograph records.

The modern tendency has been toward clocks having musical chimes, calendars and other data, 15 and my invention is particularly designed to create a novel machine or apparatus which is not only a clock but also an announcer of the time in the exact words of the language recorded.

An important object of my invention is the 20 provision of an announcing machine which includes means controlled from the clock to intermittently rotate and stop a phonograph record or the like having recorded thereon any matter which it is desired to reproduce.

25 A further object of my invention is the provision of means attachable to a standard clock and which is adapted to elevate or lower a sound reproducing element with a record, said means comprising elements actuatable and operable from a 30 rotatable control board, which control board is in turn controlled through opening and closing switches either electrical or mechanical, operable by a standard clock.

A further important object of my invention is 35 the provision, in combination with a standard clock and a sound reproducing apparatus including a record, of means to automatically and at the proper time return the sound reproducing element to the starting point on the record.

40 A further object of this invention is the provision of an apparatus cooperable with and controlled from a standard clock, which includes a motor controlled by said clock and which further comprises a control board rotatable by said motor 45 and having means for releasably locking said control board against rotation, said control board being connected through gears with a record rotat-

ing element.

45 A further object of my invention is the provision of a clock and an apparatus in combination therewith and controlled thereby which will announce the time in words at certain desired intervals, as well as announce in words in any language advertising material, including slogans, prices and 55 other matter.

Other and further important objects of this invention will be apparent from the disclosures in the specification and the accompanying drawings.

60 This invention (in a preferred form) is illus-

trated in the drawings and hereinafter more fully described.

On the drawings:

Fig. 1 is a front view illustrating an electric clock, including a clock dial and hands.

Fig. 2 is a cross sectional view taken on the line II—II of Fig. 1 and showing some of the interior mechanism.

Fig. 3 is an enlarged perspective view showing the upper wall of the box containing my mechanism and showing the means through which a reproducing element is elevated and lowered.

Fig. 4 is an enlarged perspective view of the under side of the top wall described in Fig. 3.

Fig. 5 is a cross sectional view taken from the right showing the interior mechanism including the motor, control board, record, rotating element and sound reproducing means.

Fig. 6 is an enlarged fragmentary view showing a schematic construction of the opening and closing switch whereby the control board is released and the electric circuit to the motor driving the mechanism is closed.

Fig. 7 is a top plan view showing the relative positions of the control board, the record rotating element, the reproducing element, and the means for returning the reproducing element to starting position.

Fig. 8 is a view taken from the front and showing in detail the means for raising and lowering the reproducing element and the record rotating wheel.

Fig. 9 is an enlarged detail view showing the means which I employ to rotate the arm on which the reproducing element is mounted to carry the latter to starting position.

As shown on the drawings:

The reference numeral 10 indicates the front of a clock cabinet 10' which contains sound reproducing and announcing apparatus and having an aperture for a clock face. The lower portion of the clock front 10 is preferably open except for a material such as silk, which is substantially non-resistant to sound. The ornamental front shown in Fig. 1 may be made of wood, metal or a composition material such as bakelite and merely illustrates one preferred form.

A clock 13, which is preferably an electric clock but may be an ordinary spring or weight clock, is rigidly mounted in the aperture of the front face 10 by means of suitable brackets. The clock face 10 includes a device of well known construction such as is used in chime clocks which is actuated by the clockwork at regular intervals, usually every fifteen or thirty minutes. This last mentioned device has attached thereto a rotatable shaft 14 extending outwardly from the clock cabinet, the end of which is shown in Fig. 6. A cam 15 is secured to the end of the shaft 14 in perpendicular position thereto and is of a shape

so as to release the turntable through means hereinafter described and immediately thereafter actuate a switch to effect rotation of a turntable as hereinafter described.

As shown in Figs. 2 and 5, a partition wall 17 is mounted in horizontal position to support the mechanism which will be hereinafter described and to separate the sound chamber from the remainder of the clock cabinet 10'. A sound disc plate 18 of standard construction having a downwardly extending shaft 19 is rotatably mounted on the bushing 20 which in turn is secured on the supporting wall 17. The shaft 19 extends downwardly through an aperture in the wall 17 and is connected by a flexible coupling 23 to a rotatable element of a speed reducer 21, which speed reducer is attached and driven by a motor 22 which may be electrical or mechanical. The motor 22 is preferably secured to the under side of the wall 17 by screws or the like. A small ring gear 24 is secured about the shaft 19 adjacent to and concentric with the rotatable plate 18. A tone arm, preferably made of metal and of the usual shape and which comprises an angular upper elongated portion, has one end swivelly mounted to permit horizontal movement thereof in a ring member 26 which is securely mounted on the supporting wall 17, as clearly shown in Fig. 5. A substantially U-shaped reproducing element 27, particularly shown in Fig. 7, is rotatably connected with respect to the tone arm 25 through suitable interfitting annular flanges formed on the periphery of said element and said tone arm. The reproducing element may be conveniently moved in vertical and arcuate direction and includes a vibrating diaphragm, a needle adapted to engage the sound record, and other parts which are well known in the art. The tone arm 25 with its end ring member 26 open downwardly into a gradually enlarged sound chamber 27 which preferably extends to the front of the clock, where the sound may pass through the openings in the clock cabinet face.

Rotatably mounted on the upper reduced end of a vertical post 28 which is secured a short distance from the bushing 20, is a control gear wheel 29 of slightly smaller size than the disc plate 18. The peripheral gear wheel teeth of the control gear wheel 29 are in mesh with the small ring gear 24 and are driven thereby, the ratio between the control gear wheel and said ring gear being preferably forty to one.

An upper horizontal supporting board 30 divided in two separate sections and shown clearly in Figs. 3 and 4, forms an inner cover for the cabinet 10' and also serves as a support for elevating and lowering mechanism which I will now describe. One section of said board is hinged as shown to permit convenient access to the mechanism. Relatively large apertures 31 and 32 are formed a short distance apart in said board 30 and in the position clearly shown in Fig. 3. A yoke 33 is securely mounted on the upper surface of said supporting board 30 substantially midway between said apertures, and a lever 34 is pivoted thereto by means of a pin passing therethrough at a point substantially midway between its ends. Secured on the under side of the supporting board 30 at points as indicated in Fig. 4 is a pair of channel guide members 35 and 36 in opposed position. A frame member 37 of substantially rectangular shape has its two shorter opposite sides slidably mounted in said guide members 35 and 36. The lower end of a yoke 38 is secured by riveting or the like in the center of

the upper side of the frame member 37, and the upper ends of said yoke are pivoted to the apertured end of the lever 34 as clearly shown in Figs. 7 and 8. A slideable link 39 is adapted to slide longitudinally along the lower side of the frame member 37 for a purpose which will be hereinafter explained. The slideable link 39 is connected by a plurality of metal links 40 to the reproducing element 27. It will be apparent from the construction just described that upward movement of the yoke 38 and the frame member 37 will raise the reproducing element to place the needle thereof out of engagement with the record on the revolvable plate. I will now further describe the means whereby both up and down vertical movement is effected intermittently at predetermined times.

The outer end of the lever 34 has pivoted thereto by a suitable pin, the upper bifurcated end of a rod 41. Immediately below said pivotal connection and upon the mounting board 17 is secured an apertured ear 42. Journalled in said apertured ear is a short stud shaft 43 having on one end thereof a relatively small pinion 45, and on its other end a cam 44, as clearly shown in Figs. 8 and 9. The lower end of the rod 41 is bent to form a loop which is rotatably mounted about the cam 44.

Secured by welding or the like on the under side of the control gear wheel 29 and adjacent its periphery is a short gear segment 46 mounted in an arcuate position on said gear wheel so as to mesh with the pinion 45, said gear segment being of such a length so as to rotate said pinion and connected shaft only one-half of a revolution. It will be apparent that as said gear segment rotates said pinion, the rod 41 will be moved upwardly, and due to the action of the lever 34 the slideable frame 37 and the reproducing element suspended thereon will be lowered to record-engaging position, where it will remain until removed by a counter action which will now be described.

Mounted on the control gear wheel 29 and at substantially the same point with respect to the axis of said control gear wheel, is an offset member, the outer portion of which comprises a gear segment 47 of the same length as the gear segment 46. It will be apparent that as the control gear wheel 29 advances a predetermined distance sufficient for the sound to be reproduced the offset gear segment 47 will engage the under side of the pinion 45 to rotate the same 180 degrees to lower the rod 41, which in turn will cause elevation of the sound reproducing element from record engaging position. Upon such elevation and due to the slideable engagement of the ring 39 with the frame member 37, the reproducing element and its needle will remain in exactly the same position with respect to the portion of the record which has already been reproduced, even though the record and its supporting plate continues to be rotated by the motor heretofore described. It will be seen that the reproducing element and its attached tone arm 25 will be advanced in its travel along the record only while the needle of the reproducing element is in record-engaging position.

After the offset gear segment 47 has disengaged the pinion 45 the plate 18 and the control gear wheel 29 will continue in their relative rotations until a downwardly extending stud 48 formed on the under surface of the control gear wheel 29 engages the upper end of a pin 49 which is slidably mounted in vertical position in a

bracket 50 secured on the mounting board 17. As shown in Fig. 6, a substantially horizontal lever 51, which is pivoted intermediate its ends on a post 52 and which has one end pivoted to the lower end of the slidable pin 49, is adapted to normally hold the slidable pin 49 in upper position. A counterweight 52' is formed integral with the opposite end of said lever and normally holds the pin 49 in elevated position so that it will engage the stud 48 to stop rotation of the control gear wheel 29 after one revolution thereof has been completed. A control switch 53 of conventional type and illustrated in Fig. 6, and which may also be a mechanical switch, is adapted to open and close the circuit supplying the electric motor 22 with current. Said control switch must necessarily be controlled by the clockwork and from the clock so that it may be intermittently opened and closed to energize the motor or clockwork and cause operation of my device until one revolution of the control wheel 29 has been completed. In my preferred form, the control switch 53 has a short outwardly extending lever which is pivoted in a position so that as the cam 16 is rotated by the shaft 14 of the clockwork heretofore described, the switch will be opened and closed when the shaft 14 is rotated in counter-clockwise direction. The cam 16 will close said switch immediately after it raises the counterweight 52' to release the control gear wheel 29 from locked position.

In my preferred form, a single sound record contains announcements of the time in words in logical order at fifteen minute intervals for a total period of twelve hours. It will be apparent that at the end of twelve hours the reproducing element has passed its last announcement, recorded near the center of the record, and therefore it is necessary that my device be so automatically operable that the reproducing element and tone arm will be returned to starting position immediately prior to the time when one o'clock is to be announced, and the announcements for a twelve-hour period repeated. In my preferred form I employ the following mechanism for returning said reproducing element to the beginning of the record at the proper time.

As shown in Fig. 7, a pair of right-angled brackets 54 are secured a short distance apart and at points on opposite sides of the tone arm 25. Each of said brackets has rotatably mounted thereon an idle sprocket 55. A link chain 56 is adapted to be rotated about said sprockets, the links of said chain having transversely extending studs 57. In the preferred form of my invention I have shown a chain having forty-eight links and a corresponding number of transversely extending studs. One of the forty-eight links has a vertically extending stud 58 for a purpose which will appear hereinafter. Secured on the under side of the control gear wheel 29 is a stud 59 which is so positioned on said gear wheel that upon each revolution of said gear wheel it will engage one of the studs 57 of the chain 56, which is at a point below said gear wheel, such engagement causing the chain 56 to advance the distance of one link and one stud. It is apparent, therefore, that if an announcement is made for each revolution of the control gear wheel 29, the chain 56 will have been rotated the distance of one link, and when the control wheel has rotated forty-eight times it will cause one complete revolution of the chain 56. The chain 56 is so positioned that when the reproducing element has finished the last an-

nouncement on the end of the record, the upwardly extending stud 58 will engage a stud 60 on said tone arm to return said tone arm and reproducing element to place the needle thereof in starting position on the record. As the operation proceeds the chain 56 will be advanced one link at a time as heretofore described, and until it is again necessary to return the tone arm to starting position.

Because the speed of rotation of the turntable 18 is comparatively high, it is desirable to provide means to materially reduce its speed of rotation a short interval prior to the time that the rotatable control wheel is to be locked through engagement of the stud 48 and the movable stud 49 hereinbefore described, thereby preventing a sudden stoppage of the control wheel 29 and consequent injury to the ring gear 24 which is in mesh therewith due to the inertia of the rotating turntable. One form of braking means is illustrated in Figs. 8 and 9 and comprises a vertical post 61 having its upper end bent horizontally as shown, said upper end having a vertical aperture therethrough. A yoke 62 having an upper offset portion is journalled in said aperture, the upper arm of said yoke extending in an upward and horizontal direction below the turntable 18 and immediately within the annular flange of said turntable. Said arm has mounted thereon a braking member 64 which is adapted to be moved toward the inner surface of the flange of the turntable 18 to frictionally engage the same, as will now be described. The lower arm of said yoke 62 is of a substantially resilient material such as thin spring steel and extends horizontally toward the axis of the rotatable control wheel 29. A stud 63 extending downwardly from the bottom of the rotatable control wheel 29 and at a point slightly in advance of the stud 48, will engage the lower arm of the yoke 62 a short interval prior to the time that the control wheel is to be locked to cause frictional engagement of the member 64 on the flange of the turntable 18, thereby gradually reducing the speed of said turntable as well as the speed of the control wheel 29.

The lower arm of the yoke 62, being flexible, will permit the stud 63 to pass the end thereof, immediately after which the control wheel will be locked by the stud 48 in a manner heretofore described.

It will be apparent that the mechanism described hereinbefore for intermittently lowering and elevating the reproducing element as well as the mechanism for stopping, locking, and releasing the control wheel 29 may be displaced by well known electrical means, including solenoid energized magnets and proper control switches operated by the clockwork of my device, and likewise, that the clock may be electrical or mechanical.

I am aware that many changes may be made and numerous details of the invention and construction thereof may be varied through a wide range without departing from the principles of this invention, and I therefore do not desire to limit the patent granted thereon otherwise than necessitated by the prior art.

I claim as my invention:

1. A time announcing apparatus comprising a housing; a motor; a control switch in the circuit of said motor; a record carrying turntable horizontally and rotatably mounted therein and driven by said motor; coupling means connecting said motor and turntable; a pinion secured below and concentric with said turntable and driven with

said turntable; a horizontally movable tone arm mounted adjacent said turntable and terminating in an enlarged sound chamber; a tone reproducer mounted on said tone arm adapted to move vertically and horizontally; a control gear wheel having gear teeth rotatably mounted adjacent said turntable in mesh with said pinion and driven thereby; spaced apart gear members on said control gear wheel; releasable locking means for said control gear wheel; a vertically movable frame member mounted above said reproducer; a link connection between said frame member and reproducer; and lever means for vertically moving said member and reproducer comprising a plurality of levers, a cam, a stud shaft and pinion thereon and means actuatable by said spaced apart gear members adapted to actuate said lever means.

2. A time announcing apparatus comprising a housing; a motor, a record carrying turntable horizontally and rotatably mounted in said housing and driven by said motor; a pinion secured thereon and concentric with said turntable; a control gear wheel having gear teeth rotatably mounted adjacent said turntable and in mesh with said pinion; releasable locking means for said control gear wheel; and a pair of spaced apart gear segments on said gear wheel; a horizontally movable tone arm mounted adjacent said turntable; a tone reproducer mounted on said tone arm; a rotatably mounted element adjacent said control gear wheel and intermittently engageable by said gear segments; a plurality of levers for transmitting the intermittent movement of said rotatably mounted element into vertical movement, one of said levers being connected to said tone reproducer and another thereof being engaged by said rotatably mounted element, said gear segments being adapted to intermittently engage said rotatably mounted element to impart downward or upward vertical movement to said reproducer.

3. A voice reproducing and announcing device comprising a housing; a motor, a record carrying turntable horizontally and rotatably mounted therein and driven by said motor; a pinion secured thereon and concentric with said turntable; a horizontally movable tone arm mounted adjacent said plate; a tone reproducer mounted on said tone arm adapted to move vertically; a control gear wheel having gear teeth rotatably mounted adjacent said plate and in mesh with said pinion; releasable locking means for said control gear wheel; lever means for vertically moving said reproducer comprising a plurality of levers; a cam, a stud shaft and pinion thereon; a pair of spaced apart gear segments on said control gear wheel, the forward of said gear segments being adapted to rotate said pinion to lower said frame member and reproducer to permit recorded voice reproduction, and the other of said segments being adapted to rotate said pinion in the opposite direction to cause said reproducer to be elevated; a perpendicular stud on said control gear wheel; and rotatable means mounted adjacent said tone arm adapted to be actuated at predetermined intervals by said stud to move said tone arm horizontally to place the reproducer in starting position on a record.

70 4. A voice reproducing and announcing device comprising a housing, a motor, a record carrying turntable horizontally and rotatably mounted

therein and driven by said motor; a pinion secured thereon and concentric with said turntable; a horizontally movable tone arm mounted adjacent said turntable; a tone reproducer mounted on said tone arm adapted to move vertically; a control gear wheel having gear teeth rotatably mounted adjacent said turntable and in mesh with said pinion; releasable locking means for said control gear wheel, a perpendicular stud on said control gear wheel adapted to be engaged by said releasable locking means to stop said control wheel and to be disengaged thereby to release said control wheel for rotation; lever means for vertically moving said reproducer comprising a plurality of levers, a cam, a stud shaft and pinion thereon; a pair of spaced apart gear segments on said control gear wheel, the forward of said gear segments being adapted to rotate said pinion to lower said frame member and reproducer to permit recorded voice reproduction, and the other of said segments being adapted to rotate said pinion in the opposite direction to cause said reproducer to be elevated; and means adapted to be intermittently actuated to move the tone arm and reproducer horizontally to starting position, said means comprising a pair of sprocket wheels and a chain, each of the links of said chain having an outwardly extending stud, and one or more of said links having a second stud formed integral with the edge of such links, said second stud being adapted to engage the tone arm once during each revolution of said chain to return said tone arm to starting position.

5. An intermittent sound reproducing device comprising a motor; a control switch for said motor; a record carrying turntable rotatably connected with said motor; a pinion concentric with said turntable and secured thereto; a control gear wheel rotatably mounted adjacent said turntable and in mesh with said pinion; a horizontally movable tone arm; a vertically movable sound reproducer thereon; a frame member slidably mounted above said reproducer for vertical or horizontal movement; a loose connector between said frame member and reproducer; spaced apart gear members on said control gear wheel, and means actuatable by said gear members adapted to raise and lower said frame member and reproducer.

6. An intermittent sound reproducing device comprising a motor; a control switch for said motor; a record carrying turntable rotatably connected with said motor; a pinion concentric with said turntable and secured thereto; a control gear wheel rotatably mounted adjacent said turntable and in mesh with said pinion; a horizontally movable tone arm; a vertically movable sound reproducer thereon; a frame member slidably mounted above said reproducer; a loose connector between said frame member and reproducer; spaced apart gear members on said control gear wheel; means actuatable by said gear members adapted to raise and lower said frame member and reproducer; a downwardly projecting stud on said control gear wheel; means rotatably mounted adjacent said tone arm adapted to be rotated a predetermined distance by said stud, and means on said last mentioned means adapted to engage said tone arm at a predetermined position to return said arm to starting position to repeat the sound reproduction.

MICHAEL J. SULLIVAN.
